APPARATUS FOR EXTRUDING WIDE METAL SHEETS

Karl F. Braeuninger, Gundernhausen (Darmstadt), Germany, assignor to the United States of America as represented by the Secretary of the Air Force

Application January 16, 1951, Serial No. 206,285

3 Claims. (Cl. 207—17)

(Granted under Title 35, U. S. Code (1952), sec. 266)

1

The invention described herein may be manufactured and used by or for the United States Government for governmental purposes without payment to me of any royalty thereon.

This invention relates to a method of extruding thin and wide ribbed metal sheets and particularly to the construction of extrusion dies capable of carrying out the method.

In order to produce as wide a sheet as possible in a given size extrusion press resort may be had to first producing a sheet of U-shaped cross section then flattening out the U to form a flat sheet of substantially double the width that would normally be produced in the press.

But while the foregoing procedure is highly satisfactory in that it produces a wide flat sheet in a die which is much smaller than the width of the sheet, considerable difficulty is encountered in designing and constructing a die which will stand the strains incident to extruding metal into a U-shaped cross section wherein the space between the legs of the U is small relative to their length, in which case parts of the die overhang in cantilever fashion to such an extent that they are unstable at the free ends and for that reason incapable of producing accurate sections.

Experiments have shown that most of the aluminum and magnesium alloys when in a plastic state and properly confined and subjected to appropriate pressure will divide and flow over the sides of a streamlined body. Moreover, it has been demonstrated that, when past this streamlined profile, the metals flow back together and produce an excellent weld.

It is therefore an object of the invention to provide a die capable of extruding profiles of U shape in which the bars of the U are close together relative to their length, yet so brace the free ends of the cantilever portions of the die as to maintain a high degree of accuracy in the product.

I attain this and other objects in the structure hereinafter described, reference being had to the drawings, wherein:

Fig. 1 is a top plan view of the one-piece die.

Fig. 2 is a cross section taken on the line 2—2 of Fig. 1 showing one of the bridges which supports a weaker portion of the die.

Fig. 3 is a cross section taken at 3—3 of Fig. 2 through the die proper.

Fig. 4 is a cross section taken at 4—4 of Fig. 1 showing the streamline contour of the bridge.

Fig. 5 is an axial section through the press which is used to contain the die shown in Figs. 55

2

1 to 3 and to extrude a metal billet therethrough.

Fig. 6 is a schematic view showing how the extruded metal divides and flows around the bridge and welds again.

5 Fig. 7 illustrates how the residue is removed by the trimmer of the press.

Fig. 8 shows that the grain at the place where the weld occurred is improved.

Fig. 9 shows a modified cross section whereby a

10 still wider sheet may be extruded in a given press.

Like reference characters refer to like parts throughout the several views.

Referring now to the drawings and more particularly to Fig. 3, let it be assumed that a section of sheet metal of width W—W and thickness T is to be extruded. If the available press and its die 10 will not accommodate an extruding slot 11 of the desired width W—W and thickness T in one plane, the sheet may be extruded in U shape, as shown, and flattened thereafter.

15 It is, however, extremely difficult to extrude U-shaped profiles with any appreciable degree of accuracy, particularly where the width or thickness at D is small relative to the length L, since in this case the tongue 12 of the die is a cantilever supported only at the one end E as shown, which leaves the end D otherwise unsupported. Considering that the pressure on the outer end D of the tongue 12 may be as much as 180,000 p. s. i. the deflection of the tongue at D, which 20 may be either in the direction of the pressure or transverse thereto, is such as to preclude the possibility of making accurate wall thicknesses in the finished product.

25 In order to minimize deflection of the end D of the tongue 12 during extrusion of the U-shaped profile, a bridge 14 (see Figs. 1, 2 and 4) is provided for connecting the free end D of the tongue 12 to a solid portion 16 of the die. This bridge 14 is an integral part of the die 10 proper and constitutes an important feature of the invention. It consists of a lug extending integrally upward from the top surface of the die 10, the lug having a transverse thickness somewhat less than the dimension D of the tongue 12, and has an underpass so contoured as to leave a streamlined connecting portion above the underpass.

30 This streamlined contour is that part of the bridge which remains after forming bellmouthed tunnels 18, Figs. 1, 2 and 4, in the sides of the bridge at the juncture between the bridge and the face of the die which communicate with the extruding slot 11, whereby that portion of the extruding slot 11 which falls under the bridge 14 will be supplied by that portion of the billet

which has been forced down both sides of the bridge and into the tunnels where the two sides become welded together before the metal enters the extruding slot 11.

Repeated trials have conclusively proven that the dividing of the billet metal over the bridge 14 and its subsequent rewelding in the tunnels 18 of the underpass is attributable to the streamlined cross section of the bridge. The shape of the bridge cross section is therefore considered an important feature of the invention. Fig. 6 shows how the billet metal 24 flows down over the sides of the bridge 14 and unites and welds in the underpass of the bridge. (See also Fig. 4.)

Moreover, repeated tests have demonstrated that the grain in the extruded metal at the weld is improved rather than injured (see Fig. 8).

The die 10 hereinbefore shown and described is set up in a conventional extrusion press schematically shown at 20 in Fig. 5. This press comprises a billet container 22 within which the billet 24, the die 10 and the ram 26 are concentrically positioned.

The die 10 is supported by the back-up piece 28 which is in turn held in the die holder 30. A locking member 32 is provided for retaining the parts 10, 28, 30 in the position shown pending extrusion. The extrusion operation is carried out substantially as follows:

The die 10, back-up piece 28 and die holder 30 are assembled as shown in concentric relation with the press 20 and billet container 22 and the locking member 32 entered through its slot in the press. The ram 26 is withdrawn to the left and a heated billet 24 is placed in the container 22. The ram 26 is now moved toward the right, forcing the billet 24 over the sides of the bridge 14 and through the tunnels 18 and through such portion of the extruding slot 11 as lies under the bridge 14, the remainder of the extruding slot 11 receiving metal directly from the billet 24 (see Figs. 1 and 5). Extrusion now continues until the end 34 of the ram 26 is about on the line F-F.

The locking member 32 is now withdrawn whereupon the ram 26 may be moved rightwise, thereby pushing the die 10, back-up piece 28 and die holder 30 rightwise completely clear of the billet container 22. The ram 26 is now moved leftwise away from the waste slug 36 whereupon the die and slug appear as in Fig. 7.

Fig. 7 shows the die 10 with the waste slug 36 still attached, but with the transverse trimmer cutter 38, which is a part of every extrusion press, in position for removing the waste slug from the die. By moving the cutter 38, Fig. 7, in the direction of the arrow 40, the waste slug rides up the incline 42 of the bridge 14 thereby tearing apart at G, Figs. 4 and 7, and spreading the portion of the waste which is in the tunnels 18, that is, moving the waste slug 36, Fig. 7, along the incline 42 of the bridge 36 will not only tear apart the small slugs in the tunnels but will spread them apart, due to the streamlined shape of the bridge 14. The die 14 is therefore self-cleaning, a valuable feature of the invention. Moreover, the presence of a weld, where consecutive charges meet, is avoided, such conditions, as is well known, being conducive to unsoundness. The incline 42 is also an important part of the invention.

In the foregoing I have shown equipment and a method whereby wider sheets of metal may be

extruded in a given size die by making the extrusion slot 11 in U shape instead of straight, then flattening the extruded U to compose a uni-planar sheet. It will be readily understood, however, that this method may be extended to compose still wider sheets by making the extrusion slot in an S shape as seen in Fig. 9. Still wider sheets may be extruded in the same size die by providing an extruding slot having a still greater number of convolutions than shown in Fig. 9 if the dimension D is made much narrower relative to the dimension L than shown in Fig. 9. Additionally the greater number of convolutions will call for a greater number of bridges in the die.

The invention, moreover, lends itself to the making of ribbed sheets, the ribs 44 being integral with the sheet and all on one side thereof as seen in Fig. 9, whereby, when the convolutions are flattened out, a ribbed sheet is provided which, it is contemplated, will be extensively used for making the skins of aircraft.

Having described my invention, I claim:

1. Apparatus for producing thin wide metal sheets by extrusion comprising a die member having a base portion including a thin elongated U-shaped slot therethrough providing a tongue member centrally thereof, a bridge member integral with said base portion and connecting the tongue member with the opposed base portion at the other side of the slot at its point of greatest convexity, the bridge member being spaced from said base portion above the slot and having an inclined surface at one end thereof to facilitate the separation of the waste slug from a billet being extruded through the die member and over the bridge member.

2. Apparatus for producing thin wide metal sheets by extrusion comprising a base member having a narrow elongated U-shaped extrusion slot therethrough providing a narrow tongue member therebetween, a streamlined bridge member extending from said base member and integral therewith connecting the tongue member and an opposed portion of the base member across the slot at its point of greatest convexity, the portion of the bridge member across the slot being spaced from the base member whereby metal flow past the bridge member produces a weld thereunder in the metal extruded through the slot at its point of greatest convexity.

3. Apparatus for extruding thin wide metal sheets comprising a base member having a narrow U-shaped slot therethrough providing a tongue portion thereof surrounded by said U-shaped slot, a streamlined bridge member bridging the slot at its point of greatest convexity extending from the tongue portion to the opposed portion of the base member and integral therewith whereby a U-shaped member extruded thereby will produce a wide metal sheet.
